UNITED STATES PATENT OFFICE

120,287

DESIGN FOR A TEXTILE FABRIC OR SIMILAR ARTICLE

William Steffen, Hackensack, N. J.

Application March 25, 1940, Serial No. 91,210

Term of patent 3½ years

To all whom it may concern:

Be it known that I, William Steffen, a citizen of the United States, residing in Hackensack, county of Bergen and State of New Jersey, have invented a new, original, and ornamental Design for a Textile Fabric or Similar Article, of which the following is a specification, reference being had to the accompanying drawing, forming part thereof.

The figure of the drawing is a plan view of a textile fabric or similar article, showing my new design.

I claim:

The ornamental design for a textile fabric or similar article, as shown.

WILLIAM STEFFEN.
